UNITED STATES PATENT OFFICE.

AMY S. MOERAN, OF NEW YORK, N. Y.

DESIGN FOR A GAME.

60,694.

Specification for Design. Patented Mar. 21, 1922.

Application filed October 6, 1920. Serial No. 415,171. Term of patent 3½ years.

To all whom it may concern:

Be it known that I, AMY S. MOERAN, a citizen of the United States, residing at New York, in the county of New York and State of New York, have invented a new, original, and ornamental Design for a Game, of which the following is a specification, reference being had to the accompanying drawing, forming a part thereof.

The figure is a view in elevation of a game showing my new design.

I claim—

The ornamental design for a game, as shown.

AMY S. MOERAN
